Primary Examiner — Marianne Pandozzi*(74) Attorney, Agent, or Firm* — Michael J. Corrigan(57) **CLAIM**

The ornamental design for the hot beverage maker, as shown and described.

DESCRIPTION

FIG. 1 is a front perspective view of a hot beverage maker showing my new design;

FIG. 2 is front view thereof;

FIG. 3 is a rear view thereof;

FIG. 4 is a left side view thereof;

FIG. 5 is a right side view thereof; and,

FIG. 6 is a top plan view thereof.

The broken lines depict portions of the hot beverage maker that form no part of the claimed design.
